cago, Ill., a corporation of Delaware

Application October 26, 1936, Serial No. 107,581

18 Claims. (Cl. 179—26)

This invention relates in general to telephone systems, but is concerned more particularly with operator controlled magneto exchange telephone systems, commonly referred to as remote controlled exchanges, (R. C. X.), in which connections between local subscribers are established by manual operators from a remote or distant control point.

More in particular, the present invention relates to a telephone system wherein an operator at the central office may control the switching equipment in an outlying exchange or rural office terminating local battery magneto lines either to establish connections between two subscribers in the rural office or to establish connections to the central or main office.

One object of the invention is to provide a cheap but nevertheless efficient unit for small rural communities that heretofore have been without any communicating service because the number of subscribers desiring service did not warrant the expense of the installation of a switching exchange. The switching unit in the present invention is arranged to take care of twenty subscribers' lines and is controlled over two trunk lines from the distant central office by a manual operator. The equipment in the small rural exchange operates on a 12-volt storage battery which is charged over one of the trunk lines. The release of all of the connections are under control of the remote operator.

Another object of the invention is the provision of improved circuit arrangements, whereby the control of the magneto exchange by the operator at the remote office may be brought about in a thoroughly reliable manner, while the equipment and the number of conductors required between the two exchanges over which the operator controls the setting up of connections between subscribers in the magneto exchange has been reduced to a minimum.

Other objects and features of the invention will be understood by referring to the specification and accompanying drawings comprising Figs. 1 and 2.

Fig. 1 shows two of the twenty subscribers' lines and the subscribers' individual line relays for connecting such lines to two trunk lines. Fig. 1 also shows a cut-off relay individual to each trunk line and common to all of the subscribers' lines. A common busy relay 108 is shown in the lower right-hand corner of Fig. 1 for connecting the busy tone to the trunk lines and to the calling subscribers. The dotted square shown in the lower right-hand corner of Fig. 1

represents circuit arrangements identical with those shown in Fig. 2.

Fig. 2 shows the control relays and the minor switch individual to one of the trunk lines, such trunk line extending to the remote office where it terminates in a jack.

The switch shown in the lower portion of Fig. 2 is commonly used in telephone systems and is known as a minor switch having an operating magnet for advancing the wipers step by step 10 and a release magnet for restoring the wipers of the switch to normal position. The relays shown with their lower portions cross-hatched and the relays, such as relays 270 and 280, shown with copper sleeves around the cores, are of the slow-to-release type. Relay 294 is a thermo relay which closes its contacts 293 a predetermined time after the circuit to this relay has been completed.

In describing the detailed operation of the apparatus shown it will first be assumed that the magneto subscriber S12 desires to converse with subscriber S11. In order to initiate a call the subscriber S12 operates his hand magneto in the well known manner and completes a circuit for energizing line relay 120, assuming that both trunk lines are idle, over the following circuit: from the hand generator by way of subscriber's conductor 192, back contact 151, back contact 132 of the common cut-off relay 130, left-hand winding of line relay 120, back contact 122, subscriber's line conductor 193, to the hand generator. Line relay 120 energizes over the above-traced circuit and at contacts 123 completes a locking circuit in series with relay 200 as follows: from ground by way of contact 123, right-hand winding of relay 120, conductor 104, contacts 271 and through the winding of relay 200 to battery. At back contact 122 line relay 120 opens its original energizing circuit only after its locking circuit is completed, and at front contacts 121 and 122 connects the subscriber's line conductors 192 and 193 to the trunk line conductors 102 and 103. At front contacts 124 line relay 120 prepares a point in the circuit for the busy relay 108 in case the called line is busy.

From the foregoing description it will be seen that in response to the subscriber S12 operating his hand generator the line relay 120 is energized and locked to connect the subscriber's line to the upper trunk line. In order to more fully describe the circuit operations it will now be assumed that the upper trunk line is busy at the time subscriber S12 operates his magneto. In case the upper trunk line is busy then the com-

- mon cut-off relay 130 is in operated position and the line relay 150 instead of line relay 120 will be energized and locked in response to the operation of the hand generator. When subscriber 5 S12 operates his hand magneto at a time when only the upper trunk is busy then line relay 150 is energized over the following circuit: from the hand generator by way of conductor 192, back contact 151, front contact 132, back contact 162, 10 through the left-hand winding of line relay 150, back contact 122, and over the subscriber's line conductor 193 back to the hand generator. In a similar manner line relay 150 at contact 153 closes a locking circuit through its right-hand 15 winding in series with the relay corresponding to relay 200 in the apparatus associated with the second trunk line. At back contact 152 line relay 150 likewise opens a point in its original energizing circuit after completing its locking circuit, at front contacts 151 and 152 connects the line conductors 192 and 193 to the lower trunk conductors 172 and 173, and at front contact 154 prepares a point in the circuit for the busy relay 108.
- 25 In case both the upper and lower trunks are in use, then both of the cut-off relays 130 and 160 will be in operated position. In case a subscriber should originate a call at a time when both trunk lines are busy, then no circuit is 30 completed for energizing either one of the two associated line relays because the circuits for these relays are opened at the contacts of the operated cut-off relays.
- 35 Returning now to the time when line relay 120 is operated to connect the subscriber's line to the upper trunk, it will be seen that the continued operation of the hand generator transmits ringing current through the repeating coil RC1 over the trunk conductors 232 and 233 and the repeating coil RC2 to cause the operation of the drop 40 234 in order to signal the remote operator. When the operator observes the operated condition of drop 234 such operator will insert a plug (not shown) into the jack J and converse with the 45 calling subscriber. Jack springs 235 are closed in response to the insertion of the plug into the jack J to complete a circuit for line relay 290 in the rural exchange as follows: from ground through the winding of line relay 290, through the lower 50 right-hand winding of repeating coil RC1, trunk conductor 233, lower left-hand winding of repeating coil RC2, through the impulse springs 236 of the dial, and through jack springs 235 to battery. Line relay 290 energizes over the above-traced circuit and at front contact 291 completes 55 the circuit for release relay 280. Release relay 280 energizes and at contacts 281 closes a shunt around contact 271, at contact 282 completes the circuit for the hold relay 270, and at contact 283 60 prepares a point in the impulsing circuit.
- 65 The hold relay 270 now operates and at contact 271 opens the original energizing circuit of relay 200 and the locking circuit of line relay 120 only after contacts 281 have placed a shunt there-around. It should be mentioned at this point that relay 200 energizes in series with the locking circuit of line relay 120 to complete the circuit for energizing the common cut-off relay 130 from ground by way of contact 201 and conductor 105.
- 70 At contact 202 relay 200 completes a circuit for energizing the thermo relay 294 by way of contact 273, and at contact 203 completes the circuit for operating the tone relay 204 as follows: from ground by way of back contact 274, contact 75 203, through the right-hand winding of tone relay

204, through the resistance to negative battery. Tone relay 204 thereupon operates and at contact 205 short circuits its right-hand winding to cause its deenergization. Tone relay thereupon operates in the same manner as a buzzer to induce a tone in the left-hand winding which extends through the tone condenser TC and over conductors 102 and 103, through the front contacts 122 and 121, and conductors 192 and 193, to the calling subscriber's substation set, thereby informing the calling subscriber that he has seized an idle trunk line and may again turn his hand generator to signal the distant operator. When the operator answers, as previously described, relay 270 is energized to connect a multiple ground to conductor 105 to maintain the common cut-off relay 130 in energized position, and to open the circuit at contact 273 completed by relay 200 for the thermal relay 294. At back contact 274 hold relay 270 opens the circuit to tone relay 204, whereupon the tone relay stops vibrating to disconnect tone from the calling line to thereby inform the subscriber that the operator has answered. At front contact 274 hold relay 270 prepares a point in the energizing and locking circuits of relays 220, 230, 240, and 250, at front contact 275 prepares a point in the circuit for grounding wipers 213 and 214, and at back contact 275 opens a point in the circuit to the release magnet 215 of the minor switch.

30 When the tone is removed from the trunk conductors 102 and 103 the calling subscriber advises the remote operator that a connection is desired with subscriber S11 and thereafter replaces his receiver. The remote operator now operates his dial in accordance with the digits in the called number or in accordance with the digits 1 and 1, since the telephone number of the called subscriber is number 11. In response to the operation of the dial in accordance with the first digit 1, the shunt springs 237 are operated 40 to short circuit the right-hand windings of the repeating coil RC2 and the drop 234, and on return of the dial the impulse springs 236 are momentarily opened once to cause the deenergization of line relay 290. At back contact 291 the deenergization of line relay 290 completes the circuit for operating relay 240 and series relay 270 in multiple as follows: from ground by way of back contact 291, contact 283, contact 252, where 45 the circuit divides, one path going through the winding of series relay 260 to battery, and the other path extending by way of back contact 251 and through the winding of relay 240 to battery. Relay 260, upon energizing, at back contact 261 50 opens a point in the circuit to the operating magnet 212 and at front contact 261 prepares a new operating circuit for itself in case the first digit dialled comprises more than one impulse. Relay 240, upon energizing, at contact 241 prepares a 55 point in its own locking circuit as well as a point in the energizing circuit of relay 250. Relay 250 will not energize at this time because this relay is short circuited as follows: from ground by way of front contact 274, contact 241, winding of relay 250, back contact 251, by way of back contact 252 or front contact 261, contact 283, and back contact 291 to ground. Line relay 290 reenergizes when the impulse springs 236 of the dial are closed to reestablish the energizing circuit of slow-to-release relay 280 to maintain it in operated position, and to open the short circuit around relay 250 at back contact 291. Relay 250 now energizes in series with relay 240 over the following circuit: ground by way of front contact 274, 70 75

contact 241, and windings of relays 250 and 240 to battery. At front contact 251 relay 250 prepares a point in the circuit to relay 220, at contact 252 opens a point in the original energizing circuit of relay 240, and at contact 253 prepares a point in the impulsing circuit to the operating magnet 212 of the minor switch. In case the first digit comprises more than one impulse, the series relay 260 is maintained in operated position to complete a circuit for relay 220 by way of front contact 251, upon the second deenergization of line relay 290. However, in this case, since the first digit dialled is 1, and line relay 290 is not deenergized a second time, the relay 220 is not at this time energized and the series relay 260 deenergizes after an interval. Relay 260, upon deenergizing, at back contact 261 prepares a further point in the impulsing circuit to the operating magnet 212.

10 The operator now dials the second digit of the called number, in this case the digit 1, to again cause the line relay 290 to deenergize. At back contact 291, line relay 290 completes a circuit for energizing the operating magnet 212 of the minor switch as follows: from ground by way of back contact 291, contact 283, back contact 261, contact 253, and through the winding of operating magnet 212 to battery. A branch of this circuit extends through the winding of slow-to-release series relay 210 which energizes and at contact 211 disconnects the switch wipers 213 and 214. In response to the operation of the operating magnet 212 the wipers 213 and 214 are stepped one step by means of their ratchet and pawl mechanism in the well known manner into engagement with their first set of bank contacts, and the off-normal springs 216 are closed to prepare a point in the circuit for the release magnet 215. Line relay 290 remains energized after the impulsing period is terminated so that shortly thereafter the slow-to-release series relay 210 restores. At contact 211 relay 210 completes the circuit for operating line relay 110 of the called line in case the called line is not busy. The circuit for energizing line relay 110 may be traced as follows: from ground by way of front contact 275, through the right-hand winding of tick-tone relay 206, contact 211, back contact 222, wiper 213 in engagement with its first bank contact, conductor 106, back contact 144, through the right-hand winding of line relay 110, conductor 104, contact 281, and through the winding of relay 200 to battery. Line relay 110 energizes over the above-traced circuit and completes a locking circuit for itself through its right-hand winding from grounded contact 113 by way of conductor 104 and contact 281 through the winding of relay 200 to negative battery. At front contacts 111 and 112 line relay 110 connects the subscriber's line conductors 182 and 183 to the trunk conductors 102 and 103, while at front contact 114 line relay 110 prepares a point in the circuit for busy relay 108. From the foregoing it will be seen that line relays 110 and 120 are locked in operated position and connect the two subscribers' lines S11 and S12 to the upper trunk conductors 102 and 103.

In order to complete the connection the remote operator now connects ringing current through the jack J and repeating coils RC1 and RC2 to signal both the calling and called subscribers S12 and S11. The remote operator may monitor the connection if desired, and when conversation has been completed either the calling or the called subscriber will ring off by operating his hand generator, thereby transmitting ringing generator

over the trunk to reoperate the drop 234 at the remote operator's position.

Before describing the release of the connection, it will be assumed that the called subscriber S11 was busy in a connection established over the lower trunk line, in which case the line relay 140 will be in operated position. Returning now to the time when the series relay 210 deenergizes and the wipers 213 and 214 have been stepped into engagement with their first set of bank contacts, a circuit may now be traced for operating the busy relay 108 since subscriber S11 is busy over a connection including the lower trunk line. This circuit may be traced as follows: from ground by way of front contact 275, right-hand winding of tick-tone relay 206, contact 211, back contact 222, wiper 213 in engagement with its first bank contact, conductor 106, front contact 144 of the operated line relay 140, conductor 109, and through the winding of busy relay 108 and associated resistance to battery. The busy relay 108 energizes over the above-traced circuit, and at its own contacts short circuits its own winding to cause the busy relay to deenergize, after which it immediately reenergizes over the previously traced circuit. Busy relay 108 accordingly operates in the manner of a buzzer thereby altering the circuit through the right-hand winding of the tick-tone relay 206 to induce into the left-hand winding of tick-tone relay 206 a tick-tone which is transmitted through the tone condenser TC and over the trunk conductors 102 and 103 to the calling subscriber and the remote operator. This tick-tone informs both the calling subscriber and the remote operator that the called line S11 is busy. In a similar manner the busy relay 108 is operated to transmit the busy signal in case a calling subscriber connected to the lower trunk line attempts a connection to a called subscriber's line which is busy in engagement with a connection including the upper trunk line. For example, assuming that the subscriber S12 is connected with the lower trunk line 172 and 173, and desires a connection to subscriber S11, which is engaged in a connection including the upper trunk conductors 102 and 103. In a manner similar to that described, when the remote operator operates the minor switch associated with the second trunk line (not shown but indicated in the dotted rectangle in Fig. 1), ground is extended through the wiper of the minor switch to conductor 176, front contact 114, conductor 109, and through the winding of the busy relay 108 and associated resistance to battery. In a similar manner the interrupting action of busy relay 108 induces a tick-tone into the winding of the tick-tone relay which then transmits the tick-tone to conductors 172 and 173 to the calling subscriber and to the remote operator.

The release of the established connection is under control of the remote operator. In order to release the established connection the operator removes the plug from the jack J, thereby opening the jack springs 235 to open the circuit to line relay 290 which accordingly deenergizes. Line relay 290, upon deenergizing, at front contact 291 opens the circuit of slow-to-release relay 280, which deenergizes after an interval. At contacts 281 relay 280, upon deenergizing, opens the circuit of relay 200 and the locking circuits of the line relays 110 and 120 which have been locked to conductor 104 in series with relay 200. At contact 282 relay 280 opens the circuit of hold relay 270 and at 283 opens a point in the impulsing circuit. Relay 200, upon deenergizing, 75

- at contact 201 disconnects one of the multiple grounds from conductor 105 for holding the cut-off relay 130 operated, at contact 202 opens a further point in the circuit to the thermo relay 5 294, and at contact 203 opens a point in the circuit to the tone relay 204. The line relays which were maintained in operated position over their locking windings and conductor 104, now deenergize, and assuming that relays 110 and 120 10 are these relays, then the connection from the subscribers' lines to the trunk line conductors 102 and 103 are interrupted at the front contacts 111, 112, 121, and 122. At back contacts 112 and 122, line relays 110 and 120 prepare points in 15 their initial energizing circuits which, however, are still maintained open due to the maintained energization of common cut-off relay 130. From the foregoing it is seen that the line relays 110 and 120 are deenergized in response to the operator removing the plug from the jack J and that for the time being the subscribers S12 and S11 cannot energize their line relays to initiate a call until such time as the trunk circuit is completely released.
- 25 Shortly after the deenergization of release relay 280 hold relay 270 deenergizes and at contact 271 prepares the circuit for relay 200 and the locking circuits of the associated line relays to enable the subscribers to initiate calls. At contact 272 hold relay 270 disconnects ground from conductor 105 to deenergize the common cut-off relay 130, at 273 prepares a point in the circuit to the thermo relay 294, and at front contact 274 opens the locking circuits of relays 220, 230, 30 240, and 250, to cause their deenergization if energized, at back contact 274 prepares a point in the circuit to the tone relay 204, at front contact 275 disconnects ground from the minor switch wiper 213, and at back contact 275 completes 35 the circuit for energizing the release magnet 215 of the minor switch. Release magnet 215 accordingly operates to cause the wipers of the minor switch to be restored to normal and the off-normal springs 216 to be opened. Off-normal 40 springs 216 open the circuit to release magnet 215.
- Cut-off relay 130, upon deenergizing, at the 45 back contacts of its armatures, prepares the circuits for enabling the line relays associated with the subscribers' lines to be operated in response to further initiation of calls. At back contact 134 the negative pole of the 12-volt battery is connected by way of conductor 101, the upper right-hand winding of repeating coil RC1, and thence over the trunk conductor 232, through the upper 50 left-hand winding of the repeating coil RC2, to the negative pole of battery at the remote office, thereby constituting a charging circuit for maintaining the rural exchange battery fully charged. It should possibly be mentioned that during the 55 time common cut-off relay 130 is in operated position contact 134 disconnects direct negative battery potential from conductor 101, thereby including the balance coil 292 in the trunk to balance both sides of the trunk.
- 60 In order to make a reverting call or a call in which one subscriber desires to converse with another subscriber on the same line the calling subscriber initiates the call and signals the operator in the same manner as previously described, after which the calling party replaces his receiver and the operator rings back over the trunk line without dialling to signal the desired called subscriber by transmitting the proper code ring of the called party. The calling and called 65 parties then ring off to operate the drop, where-

upon the operator removes the plug and releases the connection as previously described.

The foregoing has described the circuit operations in connection with calls to and from the subscribers in the ten group or the subscriber 5 having a first digit 1. Connections to subscribers in the twenty group or the group in which the first digit is 2 are completed in a similar manner by the remote operator dialling the digit 2 instead of digit 1. The operations are the same as 10 previously described, but in response to the second impulse of the first digit relay 220 is energized in response thereto since the series relay 260 is maintained energized during the pulsing period. This circuit may be traced as follows: 15 from ground at back contact 281, contact 283, front contact 281, front contact 251, contact 231, and through the winding of relay 220 to battery. Relay 220 energizes over the above-traced circuit to prepare a circuit for relay 230 at contact 20 221, at contact 222 and associated back contact disconnects the wiper 213 having access to the lines in the ten group, and at contact 222 and the associated front contact connects up wiper 214 having access to the lines in the twenty group. 25 When the line relay energizes after the second impulse of the first digit, the short circuit around relay 230 is opened. This short circuit may be traced as follows: ground by way of back contact 291, contact 283, front contact 261, front contact 30 251, 231, through the winding of relay 230, contact 221, front contact 274 to ground. The re-energization of relay 290 opens this short circuit with the result that relay 230 now energizes in series with relay 220. When the slow-to-release 35 series relay 210 deenergizes after completion of the dialling period of the second digit, said relay connects ground by way of armature 275, the right-hand winding of tick-tone relay 206, contact 211, front contact 222, wiper 214, and over the 40 individual conductor, not shown, through the line relay in the twenty-line group in a manner similar to that described for the ten-line group. The remainder of the connection and the release of the connection are similar to that previously 45 described.

In case the remote operator desires to complete a connection to one of the rural subscriber's lines in order to complete a connection between a distant subscriber and a rural subscriber, the 50 operator seizes one of the trunk lines, for instance the upper trunk line, by inserting the plug into jack J, thereby completing the circuit for line relay 290. Relay 290 causes the operation of the release and hold relays 280 and 270. 55 At contact 272 hold relay 270 completes a circuit over conductor 105 for operating the common cut-off relay 130 to prevent any of the rural subscribers from seizing this trunk line. The operator now dials the digits of the called rural line, 60 and assuming that the subscriber S11 is the subscriber being called, then the digits 1 and 1 are dialled to cause the wiper 213 to engage conductor 106 in the same manner as previously described. When the slow-to-release series relay 65 210 deenergizes after the impulsing period, the following circuit is completed for energizing the line relay 110: from ground by way of front contact 275, right-hand winding of tick-tone relay 206, contact 211, back contact 222, wiper 70 213 in engagement with its first bank contact individual to subscriber S11, conductor 106, back contact 144, through the right-hand winding of line relay 110, conductor 104, contact 281, and through the winding of relay 200 to battery. 75

Line relay 110 and relay 200 energize in series. Relay 200 performs no useful function at this time because it is unnecessary to apply the waiting tone to the line and disconnect it when the operator answers. Line relay 110, upon energizing, at front contact 113 again completes its locking circuit through its right-hand winding in series with relay 200, and at front contacts 111 and 112 connects subscriber's line conductors 182 and 183 to the conductors 102 and 103. The remote operator now transmits the proper ringing code to signal the desired subscriber, and in response to the called subscriber answering the connection is completed and released as previously described.

In case the remote operator fails to answer a call within a predetermined time, the thermo relay 294 is operated to cause the release of the locked line relay and the release of the trunk. When the subscriber S1/2 initiates a call line relay 120 and relay 200 energize in series, as previously described. Relay 200 at contact 202 completes a circuit by way of contact 273 for energizing the thermo relay 294. In case the operator answers before a predetermined time, then the hold relay 270 is energized as previously described to open the circuit to thermo relay 294 to prevent the closure of contact 293. In case, however, the operator fails to answer this call within a predetermined time, then the thermo relay 294 operates and closes its contact 293 thereby completing a circuit for operating the line relay 290 as follows: from ground, through the winding of line relay 290, contact 293 of the thermo relay to battery. Line relay 290, upon energizing, causes the energization of release and hold relays 280 and 270, as previously described. The latter relay at 273 opens the circuit of the thermo relay 294, thereby causing the thermo relay to open its contacts 293 and release the line relay 290. Release relay 280 and then later on the hold relay deenergize in the same manner as previously described. During the interval between the releasing of the release relay 280 and 270, contact 281 opens the circuit of relay 200 and the operated line relay 120. Due to the release of line relay 120 the upper trunk line is freed and may be used on other calls.

Having described the invention and what is considered new and is desired to be protected by Letters Patent will be set forth in the following claims.

What is claimed is:

1. In a telephone system, a plurality of subscribers' lines, two trunk lines for interconnecting said subscribers' lines, a pair of line relays individual to each subscriber's line, the first line relay of each pair for directly connecting the corresponding subscriber's line to the first of said trunk lines and the second line relay of each pair for directly connecting the corresponding subscriber's line to the second of said trunk lines, a first cut-off relay individual to said first trunk line and operable when the first trunk line is in use, a second cut-off relay individual to said second trunk line and operable when the second trunk is in use, operating circuits for each of said first line relays associated with the first trunk line normally controlled by said first cut-off relay, and operating circuits for each of said second line relays associated with the second trunk line jointly controlled by said first and second cut-off relays.

2. In a telephone system, a plurality of sub-

scribers' lines, two trunk lines for interconnecting said subscribers' lines, a pair of line relays individual to each subscriber's line, the first line relay of each pair being associated with the first of said trunk lines for directly connecting the corresponding subscriber's line to said first trunk line, the second line relay of each pair being associated with the second of said trunk lines for directly connecting the corresponding subscriber's line to said second trunk line, a first cut-off relay individual to said first trunk line and operable when said first trunk line is busy, a second cut-off relay individual to said second trunk line and operable when said second trunk line is in use, operating circuits for each of said first line relays associated with said first trunk line normally controlled by said first cut-off relay and the corresponding subscriber's second line relay, and operating circuits for each of said second line relays associated with said second trunk line jointly controlled by said first and second cut-off relays and the corresponding subscriber's first line relay.

3. In a telephone system, a plurality of subscribers' lines, a plurality of line relays for each subscriber's line, said line relays divided into groups each group containing only one line relay for each line, a plurality of cut-off relays common to said lines, one cut-off relay for each group of line relays, an energizing circuit for each line relay in one group including normally closed contacts on the corresponding group cut-off relay and the talking conductors of the corresponding subscriber's line; and an energizing circuit for each line relay in another group including normally closed contacts on the corresponding group cut-off relay, normally open contacts on the first mentioned group cut-off relay, and the talking conductors of the corresponding subscriber's line.

4. In a telephone system, a plurality of subscribers' lines, a plurality of line relays for each subscriber's line, said line relays divided into groups each group containing only one line relay for each line, a plurality of cut-off relays common to said lines, one cut-off relay for each group of line relays; an energizing circuit for each line relay in one group including the talking conductors of the corresponding subscriber's line, normally closed contacts on the corresponding line relays in each group, and normally closed contacts on the corresponding group cut-off relay; and an energizing circuit for each line relay in another group including the talking conductors of the corresponding subscriber's line, normally closed contacts on the corresponding line relays in each group, and normally closed contacts on the corresponding group cut-off relay.

5. In a telephone system, a plurality of subscribers' lines, a plurality of line relays for each subscriber's line, a plurality of cut-off relays common to all said subscribers' lines, an energizing circuit for some of the line relays including normally closed contacts on one of said cut-off relays and the talking conductors of the corresponding subscriber's line; and an energizing circuit for other of said line relays including normally open contacts on said one cut-off relay, normally closed contacts on another of said cut-off relays, and the talking conductors of the corresponding subscriber's line.

6. In a telephone system, a plurality of subscribers' lines, a plurality of trunk lines, an individual subscriber's line relay for each trunk line

- for connecting the subscribers' lines to said trunk lines, a cut-off relay for each trunk line, each cut-off relay being common to all said subscribers' lines, an automatic switch for each trunk line for selecting called subscribers' lines, individual subscriber connections from each switch to said line relays, a first operating circuit for each line relay, including the loop of the corresponding calling subscriber's line and contacts on said common cut-off relays, and a second operating circuit for each line relay including said switch and said individual subscriber connections.

7. In a telephone system, a plurality of subscribers' lines, a first and a second line relay for each line, a pair of normally closed contacts on each line relay, a first and a second means for selecting called subscribers' lines, individual subscriber connections extending from said first selecting means to one of said contacts on each of said first line relays, individual subscriber connections extending from said second selecting means to one of said contacts on each of said second line relays, an operating circuit for each of said first line relays including the corresponding individual connection from said second selecting means and said pair of contacts on the corresponding second line relay, an operating circuit for each of said second line relays including the corresponding individual connection from said first selecting means and said pair of contacts on the corresponding first line relay, and means for operating said selecting means to complete said operating circuits.

8. In a telephone system, a plurality of subscribers' lines, a line relay individual to each subscriber's line, means for operating the individual line relays in response to corresponding lines initiating calls and being called, a busy relay for generating and transmitting a busy tone to a calling line, normally open contacts on each line relay normally connected to said busy relay, and a circuit including the said normally open contacts on the line relay of the called line for operating said busy relay and completed in case the called line is busy.

9. In a telephone system, a plurality of subscribers' lines, a line relay individual to each subscriber's line, means for operating the individual line relays in response to corresponding lines initiating calls and being called, a busy relay for generating and transmitting a busy tone to a calling line, normally open contacts on each line relay normally connected to said busy relay, a circuit including the said normally open contacts on the line relay of the called line for operating said busy relay and completed in case the called line is busy, and a second circuit inductively coupled to said first circuit for transmitting a busy tone to the calling line.

10. In a telephone system, a plurality of subscribers' lines, a first and a second line relay for each line, an armature spring having a front and a back contact on each line relay, a first and a second means for selecting called subscribers' lines, individual subscriber connections extending from said first selecting means to the armature springs on each of said first line relays, individual subscriber connections extending from said second selecting means to the armature springs on each of said second line relays, an operating circuit for each of said first line relays including the corresponding individual connection from said second selecting means and the armature spring and back contact on the corresponding second line relay, an operating circuit for each of said second line relays including the corresponding individual connection from said first selecting means and the armature spring and back contact on the corresponding first line relay, a busy relay common to said lines for generating and transmitting a busy tone to a calling line, and an operating circuit for said busy relay including any one of said individual connections and its associated armature spring and front contact.

11. In a telephone system, a plurality of subscribers' lines, a first and a second line relay for each line, an armature spring having a front and a back contact on each line relay, a first and a second means for selecting called subscribers' lines, individual subscriber connections extending from said first selecting means to the armature springs on each of said first line relays, individual subscriber connections extending from said second selecting means to the armature springs on each of said second line relays, an operating circuit for each of said first line relays including the corresponding individual connection from said second selecting means and the armature spring and back contact on the corresponding second line relay, an operating circuit for each of said second line relays including the corresponding individual connection from said first selecting means and the armature spring and back contact on the corresponding first line relay, a busy relay common to said lines for generating and transmitting a busy tone to a calling line, and multiple connections connecting each of said front contacts to said busy relay for operating said busy relay in case a busy line is selected by either one of said selecting means.

12. In a telephone system, a plurality of subscribers' lines, line relays individual to each line, an armature spring having a front and a back contact on each line relay, means for selecting called subscribers' lines, individual subscriber connections extending from said selecting means to said armature springs of said line relays, an operating circuit for each line relay including one of said individual subscriber connections and an armature spring and back contact of one of said line relays and completed in response to said selecting means selecting an idle called line, a busy relay common to said lines for generating and transmitting a busy tone to the calling line, and an operating circuit for said busy relay including one of said individual subscriber connections and an armature spring and front contact of one of said line relays and completed in response to said selecting means selecting a busy called line.

13. In a telephone system wherein an operator in a distant main exchange controls the establishment and the release of local connections in a local exchange between local subscribers' lines terminating in the local exchange, a first and a second trunk line connecting said main and local exchanges, a first line relay individual to a calling local line operated in response to the local line initiating a call for directly connecting said local line to the first trunk line in case the first trunk line is idle, a second line relay individual to said calling local line operated in response to said initiated call for directly connecting said local calling line to said second trunk line in case the first trunk line is busy, and a line relay individual to the called local line operated in response to control exercised over said connected trunk line by the operator for directly connecting the called line to said connected trunk line thereby com-

pleting a telephone connection between said local calling and called lines.

14. In a telephone system wherein an operator in a distant main exchange controls the establishment and release of local connections in a local exchange between local subscribers' lines terminating in the local exchange, a first and a second trunk line connecting said main and local exchanges, means individually associated with a calling local line and operative in response to the initiation of a call on the associated line for connecting said calling line to said first trunk line in case said first trunk line is idle, means individually associated with said calling line and operative in response to the initiation of the call on the associated line for connecting said calling line to said second trunk line in case the first trunk line is busy, and means individually associated with a called one of said local lines and operative in response to control exercised by the operator over the one of said trunk lines which is connected to said calling line for connecting the called line to said one trunk line, thereby to complete a telephone connection between said calling and called lines.

15. In a telephone system, a plurality of subscriber's lines, a pair of trunk lines, means associated with each subscriber's line and normally responsive to the initiation of a call on the associated line for connecting the associated line to one of said trunk lines, normally inoperative means associated with each subscriber's line and adapted to be conditioned to operate in response to the initiation of a call on the associated line to connect the associated line to the other of said trunk lines, and means responsive to the operation of any one of said first-named means for preventing the other similar first-named means from operating in response to the initiation of calls on their respective associated lines and for conditioning all of the said second-named means for operation.

16. In a telephone system, a plurality of subscriber's lines, a pair of trunk lines, means associated with each subscriber's line and normally responsive to the initiation of a call on the associated line for connecting the associated line to one of said trunk lines, normally inoperative means associated with each subscriber's line and adapted to be conditioned to operate in response to the initiation of a call on the associated line to connect the associated line to the other of said trunk lines, means responsive to the operation of any one of said first-named means for preventing the other similar first-named means from operating in response to the initiation of calls on their respective associated lines and for conditioning all of the said second-named means for operation, and operator controlled means for

causing any selected one of said first or second-named means to operate.

17. In a telephone system, a main exchange, a sub-exchange, a pair of trunk lines extending between said exchanges, an operator's station in said main exchange and associated with said trunk lines, an impulsive device at said station, a plurality of subscribers' lines extending to said sub-exchange, means associated with each subscriber's line and normally responsive to the initiation of a call on the associated line for connecting the associated line to one of said trunk lines, normally inoperative means associated with each subscriber's line and adapted to be conditioned to operate in response to the initiation of a call on the associated line to connect the associated line to the other of said trunk lines, means responsive to the operation of any one of said first-named means for preventing the other similar first-named means from operating in response to the initiation of calls on their respective associated lines and for conditioning all of said second-named means for operation, and means responsive to impulses transmitted from said impulsive device over said one trunk line for causing a selected one of said first-named means to operate to connect the associated line to said one trunk line.

18. In a telephone system, a main exchange, a sub-exchange, a pair of trunk lines extending between said exchanges, an operator's station in said main exchange and associated with said trunk lines, an impulsive device at said station, a plurality of subscriber's lines extending to said sub-exchange, means associated with each subscriber's line and normally responsive to the initiation of a call on the associated line for connecting the associated line to one of said trunk lines, normally inoperative means associated with each subscriber's line and adapted to be conditioned to operate in response to the initiation of a call on the associated line to connect the associated line to the other of said trunk lines, means responsive to the operation of any one of said first-named means for preventing the other similar first-named means from operating in response to the initiation of calls on their respective associated lines and for conditioning all of said second-named means for operation, means responsive to impulses transmitted from said impulsive device over said one trunk line for causing a selected one of said first-named means to operate to connect the associated line to said one trunk line, and means responsive to the selection of any one of said means associated with a busy one of said subscribers' lines for applying a busy tone current to said one trunk line and to the calling one of said subscriber's lines.

EDWARD S. PETERSON.
